UNITED STATES PATENT OFFICE.

LARS BRUUN, OF SKIEN, NORWAY.

TENONING-MACHINE.

1,382,621.

Specification of Letters Patent. Patented June 28, 1921.

Application filed January 6, 1920. Serial No. 349,744.

To all whom it may concern:

Be it known that I, LARS BRUUN, subject of the King of Norway, and resident of Skien, Norway, have invented certain new and useful Improvements in Tenoning-Machines, of which the following is a specification.

The present invention relates to an improved tenoning-machine, the principal feature of which is the simple and easy way in which the cutters may be adjusted mutually as well as in relation to the frame.

The invention is illustrated in the accompanying drawings in which:

Figure 1 is a side view of the machine.

Fig. 2 is a front view of the machine.

Fig. 3 shows a portion of the machine partially in section.

Fig. 4 is a plan view of a portion of the machine with some details shown in section.

Figs. 3 and 4 are drawn up on a somewhat larger scale than Figs. 1 and 2.

The machine is of the known type with two horizontal and two vertical cutter-spindles which are driven by belt transmissions independently of each other.

The machine comprises a frame —1— which consists of a base part, and a top frame connected to this. This top frame 30 has a vertical dove-tail guide along which the two slides —2— and —3— may be raised. Each of the said slides carries a horizontal cutter-spindle. Upon the top frame an arm —5— is arranged which carries the screw 35 spindle —6—, which supports the slides —2— and —3— and by means of which these slides may be adjusted. The spindle —6— is equipped with a hand-wheel —7—, which is threaded upon the spindle and may rotate 40 in the head or sleeve —8— of the arm —5—, but is prevented from vertical movement in relation to this by means of a nut —9—, which is threaded upon the lengthened nave of the hand-wheel and lies close up to the 45 lower side of the head —8—. The spindle —6— is prevented from rotating by means of a key —48—, which engages a groove in the spindle so that this may be raised and lowered freely.

50 The slide —2— is connected to the spindle —6— by means of the hand-wheel —11— which is screwed down upon the spindle and which is seated between a shoulder —13— on the slide and a ring —12— rigidly connected to the slide.

The slide —3— is connected to the spindle

—6— by means of the hand-wheel —14— which above is seated against the ring —15—, which is rigidly connected to the slide, and below is seated against the shoulder —13— on the slide.

It will be understood that a rotation of the hand-wheel —7— will cause both the slides —2— and —3— to move upward or downward so that their mutual distance is not altered, but when the hand-wheels —11— and —14— are rotated, the slides —2— and —3— will be adjusted in relation to each other.

In the slides —2— and —3— the horizontal cutter spindles —40— and —41— are rotatably carried in cylindrical sleeves —40'—, —41'— which, in turn, are seated in horizontal openings in the slides. The outer portions of these sleeves are provided 75 with hand-wheels —40²— and —41²— by means of which they may be turned, and said portions are externally threaded for engagement with threads formed on the adjacent portions of the walls of the above-mentioned 80 openings, so that when said hand-wheels are turned, the sleeves may be adjusted horizontally in relation to the slides. The spindles —40— and —41— are driven by means of the two belt pulleys —38—, —39—.

To limit the adjusting movement the slides —2— and —3— are formed with vertical slots —17— and —19— through which project pins —18— fixed to the frame 1. The hand-wheels —11— and —14— are accessible 90 through openings —16— in the slides.

In the upper portion of frame —1— are formed two pair of horizontal dove tail guides —26— in which are mounted the two slides —24— for the upper and lower vertical cutter spindles 43 and 45. The slides are 95 preferably strengthened by ribs —25—.

The lateral adjustment of each of these spindles is effected by means of a threaded spindle —21—, which engages a nut —22—, 100 which is rigidly connected to the slide —24—. The spindles —21—, which in a suitable way are prevented from axial movement, carry hand-wheels —20—. The rotation of these hand-wheels will effect the 105 displacement of the slides. In the slides —24— the vertical cutter-spindles —43— and —45— are mounted in cylindrical sleeves —43'— and —45'— having threaded portions and provided with hand-wheels 110 —43²— and —45²— so that they can be rotated and hence adjusted axially. The

spindles —43— and —45— are driven by belt-pulleys —42— and —44— on their outer ends.

The work piece is placed upon a table 5 —36— provided with depending rails —34— and —35—. The cutters being adjustable, a special adjusting mechanism for the table becomes superfluous.

The table is preferably carried by a 10 bracket —27— connected to frame —1— and carrying vertical standards —28—, —29—. The upper edges of these form guides for the pairs of rolls —31—, —33— upon which the table rails —34— and 15 —35— rest. Each pair of rolls —31—, —33— is preferably connected by a shaft —32— and the standards —28—, —29— are strengthened by means of stays —30—.

Having now particularly described and 20 ascertained the nature of my said invention and in what manner the same is to be performed, I declare that what I claim is:—

1. In a tenoning machine, the combination of a frame provided with a guide; a 25 slide adjustably engaged with said guide and having an opening, a portion of which is threaded; a cylindrical sleeve projecting through said opening and adapted to move bodily with the slide, said sleeve having an 30 externally threaded portion which is engaged with the threaded portion of the opening; means connected to said sleeve to effect its rotation and consequent endwise movement through said opening; a cutter 35 spindle rotatably mounted in the sleeve to move endwise therewith; means carried by said spindle for effecting its rotation; and means independent of the sleeve-adjusting means for effecting adjustment of the slide.

40 2. In a tenoning machine, the combination of a frame provided with a vertical guide; upper and lower slides adjustably engaged with said guide; a horizontally-adjustable cutter spindle mounted in each 45 slide; a vertical spindle passing loosely through both slides and having upper and lower threaded portions; means for holding the vertical spindle against rotation; a rota-

table hand-wheel carried by said frame and threaded on said vertical spindle to effect 50 its endwise adjustment; and a pair of hand-wheels carried by said slides and engaged with the adjacent threaded portions of the vertical spindle to effect vertical adjustment 55 of either slide independently of and relatively to the other slide; the second-named hand-wheels connecting said slides to the vertical spindle for simultaneous vertical movement in either direction consequent 60 upon the movement of said spindle by the first-named hand-wheel.

3. In a tenoning machine, the combination of a frame provided with a vertical guide; upper and lower slides adjustably engaged with said guide, each slide having 65 both a vertical and a horizontal slot; a horizontally-adjustable cutter spindle mounted in each slide; a vertical spindle passing loosely through both slides and having upper and lower threaded portions; 70 means for holding the vertical spindle against rotation; a rotatable hand-wheel carried by said frame and threaded on said vertical spindle to effect its endwise adjustment; a pair of hand-wheels carried by said 75 slides and extending outwardly through said horizontal slots to permit their manipulation from outside the machine; said hand-wheels being engaged with the adjacent threaded portions of the vertical spindle to 80 effect vertical adjustment of either slide independently of and relatively to the other slide, and acting to connect both slides to the vertical spindle to move vertically in unison therewith during the movement of 85 said spindle by the first-named hand-wheel; and fixed stops carried by the frame and projecting through the vertical slots in the slides to limit their vertical movement in either direction.

Signed at Christiania this 6th day of December, A. D., 1919.

LARS BRUUN.
